(57) **CLAIM**

The ornamental design for a sensor with wireless communication function as shown and described.

DESCRIPTION

FIG. 1 is a front view of a sensor with wireless communication function of the first embodiment of our new design; FIG. 2 is a rear view thereof; FIG. 3 is a top plan view thereof; FIG. 4 is a bottom plan view thereof; FIG. 5 is a right side view thereof; FIG. 6 is a left side view thereof; FIG. 7 is a front perspective view thereof; and FIG. 8 is an enlarged sectional view taken along the line 8-8 of FIG. 1 of the portion defined by the line 8'-8' of FIG. 3. FIG. 9 is a front view of a sensor with wireless communication function of the second embodiment of our new design; FIG. 10 is a rear view thereof; FIG. 11 is a top plan view thereof; FIG. 12 is a bottom plan view thereof; FIG. 13 is a right side view thereof; FIG. 14 is a left side view thereof; FIG. 15 is a front perspective view thereof; and, FIG. 16 is an enlarged sectional view taken along the line 16-16 of FIG. 9 of the portion defined by the line 16'-16' of FIG. 11. The broken lines show portions of a sensor with wireless communication function that form no part of the claimed design.
